SHEET MATERIAL DISPENSER FOR VERTICAL ROLLS

Edward Waltz, Grand Rapids, Mich., assignor to The
E.O. Manufacturing Company, Inc., Grand Rapids,
Mich., a corporation of Michigan

Filed Feb. 11, 1969, Ser. No. 15,739

Term of patent 14 years

Int. Cl. D12—02

U.S. Cl. D14—3

FIG. 2

FIG. 1

Des. 216,964

PAGE 2

FIGURE 1 is a perspective view of a sheet material dispenser for vertical rolls embodying my new design;

FIGURE 2 is a top plan view thereof;

FIGURE 3 is an end view thereof, the opposite end being substantially a mirror image thereof;

FIGURE 4 is a side elevational view thereof;

FIGURE 5 is a perspective view of a modified sheet material dispenser;

FIGURE 6 is a perspective view of another modified sheet material dispenser;

FIGURE 7 is an end view thereof, the opposite end being substantially a mirror image thereof; and

FIGURE 8 is a top plan view thereof.

The paper rolls shown in broken lines are included for illustrative purposes only.

I claim:

The ornamental design for a sheet material dispenser for vertical rolls, as shown and described.
